UNITED STATES PATENT OFFICE.

OTTO J. KUHLKE, OF AKRON, OHIO, ASSIGNOR TO THE KUHLKE MACHINE COMPANY,
OF AKRON, OHIO, A CORPORATION OF OHIO.

VULCANIZER.

Application filed March 19, 1925. Serial No. 16,697.

To all whom it may concern:

Be it known that I, Otto J. Kuhlke, a citizen of the United States, and a resident of Akron, county of Summit, State of Ohio, have invented certain new and useful Improvements in Vulcanizers, of which the following is a specification.

This invention relates to vulcanizers, and while it is designed particularly and especially for the vulcanization of endless elastic bands such as tire flaps, the principles of the invention may be extended for other purposes and for wider utility.

The object of the invention is to construct a vulcanizer for the curing of trough-shaped rubber flaps, the invention having to do with a mechanism which will be quickly and easily operated and which will satisfactorily vulcanize the flaps in a short space of time and without loss of material. It is a further advantage of the invention that the flaps as cured in this apparatus require little if any trimming in order to finish them, thus saving material and labor.

In the drawings and description there is shown one form of the invention, it being understood that changes and modifications may be made within the scope of the invention as set forth in the claims attached hereto.

In the drawings:

Figure 1 is a side elevation of the improved vulcanizer, a portion being broken away to show the interior construction;

Figure 2 is a front view with the vulcanizer in closed position;

Figure 3 is a plan view:

Figure 4 is a front view of the vulcanizer in open position;

Figure 5 is a cross-section on the line 5-5 of Figure 2;

Figure 6 is a cross-section on the line 6-6 of Figure 2.

The vulcanizer of the present invention comprises a drum or form which is provided with a circumferential trough or channel of the shape of the inner surface of the band of elastic material or tire flap. About the drum is arranged an expandible jacket which is provided with mechanism by which the jacket is opened and closed and at the same time spaced from the drum. The jacket is provided with a rib shaped to correspond to the outer surface of the band and

to enter within the channel. The drum is provided with expandible chambers or air bags which exert pressure upon the material to shape it properly and the jacket is formed with a chamber adapted to receive steam for vulcanization, although other heating arrangements may be made. The drum is rotatably and slidably mounted, as will be explained, to facilitate the placing of the uncured flap and the removal of the completely vulcanized flap from the machine.

The mechanism herein shown comprises a base member 1 which is provided with the vertical standard 2 which supports the various elements of the device. At the center of the standard is arranged a bearing 3 in which is secured the horizontal shaft 4 which projects outwardly beyond the standard and slidably supports the freely rotatable drum or form 5, which is movable upon the shaft in the manner stated so as to permit the easy insertion and removal of the flap. The drum is provided with an outer peripheral portion 6 which is formed with a central groove or channel 7 of the shape of the flap.

Lying within the enclosed side walls of the channel are two expandible wall members or air bags 8 adapted to be inflated by air or other fluid under pressure through valves 9. A strip of covering material 14 may be placed over the bags to cover the cracks at the sides of the bags and afford a smooth surface. Pressure is transmitted to these air bags through flexible pipes 10 which are connected by a T-coupling 11 to a passageway 40 through the shaft which receives the air under pressure from an air inlet pipe 12 which passes through the central shaft 4. By connecting the bags flexibly the air connections do not interfere with the free rotation or sliding of the drum, the drum being shown in full lines in Figure 1 in the curing position, the stripping position being shown in dotted lines. In order to relieve any strain upon the pipes 10 in the rotation of the drum, the coupling 11, which is swiveled in the end of the shaft, carries a rod or closed pipe 41 which passes through a hole 42 in one of the drum spokes. This operates as a dog to turn the coupling with the drum.

The outer jacket 15 of the machine is in

the form of two semi-circular casings or plates provided upon their inner faces with a projecting rib 16 which enters the groove and forms the outer surface of the molding cavity. The jackets 15 are chambered, as shown at 18, for the reception of steam; the inlet and drain pipes for which are shown at 19 and 20, respectively.

The two jackets 15 are hinged together at the base of the machine by a pin 21 passing through the lugs 22 on the jackets, one of the lugs being extended to and pivoted at 23 upon a support 24 situated at the base of the machine, so that the whole jacket is pivotally supported on the base.

The two jacket sections 15 are adapted to be opened and closed and simultaneously moved away from or toward the drum, the double pivotal arrangement of the jacket sections permitting this result. In order to move the jacket sections each one is provided with a lug 28 to which is pivotally connected a curved rack 29, the two racks being oppositely faced and lying upon either side of and meshing with an operating pinion 30 carried upon a crank shaft 31, which is rotatably mounted in a bracket 32 secured to the upper end of the upright 2. As the crank 31 is rotated the jacket sections will open and close between the positions shown in Figures 2 and 4, it being observed that in the position shown in the latter or open view the drum 5 may be drawn outwardly along the shaft to the position where it is most easily operated upon. The last tooth 32 of each rack is enlarged as shown in Figure 3 and operates as a stop or means for suspending the jacket sections in open position.

In order to clamp the jacket sections 15 together, any suitable mechanism may be provided. For this purpose, I have shown a swinging link 34 attached to one of the jacket sections and having a swinging cam lock 35 at its free end receivable over the lug 36 upon the end of the other jacket section. A tight clamping of the two jacket sections is thereby attained.

The operation and advantages of the device will be readily understood by those skilled in the art, and it will be observed that detailed adherence to the exact construction is not necessary to obtain the full benefits of the invention. In the manufacture of flaps, the operator, having moved the drum to the outer end of the shaft 4, places a band of unvulcanized rubber upon the drum. When the rubber is properly positioned, the drum is moved backwardly in line with the jacket sections, which are open in the position shown in Figure 4. Rotation of the crank 31 moves the jacket sections together and raises them to closed position and the jacket is locked by the device 34. Air pressure is then admitted to the bags 8 by opening the cock 12, and steam being ad-

mitted to the jackets the flap is cured between the hot surface of the jackets and the air bags. A reversal of the operations permits the removal of the cured flap which will be found to be perfectly cured to shape, 70 without waste.

What is claimed is:

1. In an apparatus for vulcanizing tire flaps or the like, a form having a substantially V-shaped cavity on its outer surface, a 75 plate over the form having a V-shaped rib adapted to fit within the cavity, and expandable air bags seated within the form and constituting the inclined walls of the vulcanizing chamber.

2. In an apparatus for vulcanizing tire flaps or the like, a form having a substantially V-shaped cavity in its outer surface, a 80 plate over the form having a V-shaped rib adapted to fit within the cavity, and an expandable air bag seated within the form and constituting an inclined wall thereof.

3. In an apparatus for vulcanizing tire flaps or the like, a circular form having a substantially V-shaped cavity in its periphery, a sectional jacket about the form, a rib 85 upon the inner surface of the jacket and adapted to enter the cavity, and an expandable air bag seated within the form and constituting an inclined wall thereof.

4. In an apparatus for vulcanizing tire flaps or the like, a circular form having a substantially V-shaped cavity in its periphery, a sectional jacket about the form, and an expandable air bag seated within the form 90 and constituting a wall of the cavity.

5. In an apparatus for vulcanizing tire flaps or the like, a circular form having a substantially V-shaped cavity in its periphery, a sectional jacket about the form, and expandable air bags lying within a wall 95 of the cavity.

6. In an apparatus of the character described, a circular form, a sectional jacket surrounding the form, a hinge connection 100 between the jackets, a rocking support for the hinge, pivoted oppositely faced racks attached to the ends of the jackets, and a pinion intermeshing with said racks.

7. In an apparatus of the character described, a circular form, a sectional hinged jacket surrounding the form, a rocking support for the jacket at the hinge, and means 110 to open the hinged jacket and move it simultaneously upon its support.

8. In an apparatus of the character described, a vertical circular form, a sectional hinged jacket surrounding the form, an extension upon one section of the jacket, a pivot for the extension, and means to open 115 the hinged jacket and simultaneously lower it upon the pivot.

9. In an apparatus of the character described, a circular form, a sectional hinged jacket surrounding the form, a rocking sup- 120

port for the jacket at the hinge, a rack attached to each end of the jacket, and a pinion intermeshing with the racks.

10. In an apparatus of the character described, a circular form, a sectional hinged jacket surrounding the form, a rocking support for the jacket at the hinge, a rack attached to each end of the jacket, a pinion intermeshing with the racks, and a stop for supporting the jacket in open position.

11. In an apparatus of the character described, a circular form, an expansible bag within the form and forming one wall of a vulcanizing cavity therein, a shaft upon which the form is slidable, a flexible conduit to the bag, an expansible chambered jacket surrounding the form, means for conducting steam to the jacket, and mechanism adapted to expand the jacket and simultaneously lower it away from the form.

12. In an apparatus of the character described, a circular form, an expansible bag within the form and forming one wall of a vulcanizing cavity therein, a shaft upon

which the form is slidable and rotatable, a flexible conduit to the bag, an expansible chambered jacket surrounding the form, means for conducting steam to the jacket, and mechanism adapted to expand the jacket and simultaneously lower it away from the form.

13. A jacket for a vulcanizer comprising a pair of plates hinged together, a pivotal support for the jacket, and means for moving the plates about their hinge and also moving the jacket upon the pivot.

14. A jacket for a vulcanizer comprising a pair of plates hinged together, a pivotal support for the jacket, and rack mechanism for moving the plates about their hinge and at the same time moving the jacket upon the pivot.

15. A jacket for a vulcanizer comprising a pair of plates hinged together, a movable support for the jacket, and mechanism for opening the plates about their hinge and simultaneously moving the support.

OTTO J. KUHLKE.
